ENDLESS CONVEYOR DITCH DIGGING MACHINE

Edwin Malzahn, Perry, Okla.

Application January 2, 1953, Serial No. 329,289

2 Claims. (Cl. 37—86)

This invention relates to a ditch digging machine. The object of the invention is to provide a machine which will facilitate the digging of ditches, the present invention being portable and light in weight so that it can be readily moved from place to place as needed, the present invention being adjustable so that the rate of digging can be varied as desired.

Another object of the invention is to provide a ditch digging machine which is adapted to be used by plumbers, contractors, water departments, gas companies and the like whereby trenches can be dug at the lowest possible cost and in the least possible time, and wherein ditches of various widths can be cut, the present invention being suitable for preparing ditches and trenches for the laying of pipes and conduits, as well as for digging foundations for houses and the like.

Another object of the invention is to provide a ditch digging machine which includes self cleaning buckets, a manually operable means for causing the machine to travel in a horizontal direction, as well as a novel means of transmitting power and impact.

A further object of the invention is to provide a ditch digging machine which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of the ditch digging machine, constructed according to the present invention.

Figure 2 is a top plan view of the ditch digging machine, with the motor removed and taken on the line 2—2 of Figure 1.

Figure 3 is a rear elevational view of the machine of the present invention.

Figure 4 is a fragmentary sectional view showing a portion of the manually operable means for propelling the machine.

Figure 5 is a fragmentary sectional view showing the bucket construction of the excavator assembly.

Figure 6 is a view taken at right angles to the view shown in Figure 5.

Referring in detail to the drawings, the numeral 20 designates a frame which includes a pair of spaced apart beams 21. A rear axle 22 is connected to the frame, and a pair of suitable wheels 23 are mounted on the axle 22. There is further provided a front axle 24 which has a pair of wheels 25 mounted thereon.

A manually operable means is provided for steering the machine of the present invention and this steering mechanism includes a post 26 which has a steering wheel 27 mounted on its upper end. A hand grip 28 may be secured to the steering wheel 27, and the lower end of the post 26 is secured within a collar 29. Connected to the lower end of the post 26 is a sprocket 30 which has a chain 31 trained thereover. A second sprocket 32 of larger diameter than the sprocket 30 is mounted

2

on a shaft 33, and the chain 31 is trained over the sprocket 32. Thus, upon rotation of the sprocket 30 by means of the steering wheel 27, the sprocket 32 will also be rotated. An eccentric pin 34 connects one end of a link 35 to the sprocket 32, and the other end of the link 35 is connected to a tie rod 36. A lever 38 extends between the tie rod 36 and a second tie rod 37 so that upon rotation of the steering wheel 27 the wheels 25 can be turned so that the machine of the present invention can be guided or steered accurately.

Extending between the front ends of the beams 21 is a brace 39, while extending between the rear ends of the beams 21 is a second brace 40. A bracket 41 extends upwardly from the frame 20 and is secured thereto, and a base 42 is pivotally connected to the bracket 41 by a pin 43. A suitable motor 44 which may be powered by gasoline is supported on the base 42 and rigidly secured thereto. The motor 44 serves to rotate a drive shaft 45, and trained over a pulley mounted on the drive shaft 45 is a belt 46. There may be more than one of the belts 46 provided, and the pulley on the shaft 45 is indicated by the numeral 48.

Arranged rearwardly of the frame 20 is an excavator mechanism which is indicated generally by the numeral 50. This mechanism includes the driven shaft 47 which has a pulley 49 mounted thereon, and the belts 46 are trained over the pulleys 49.

The excavator 50 further includes a lower sprocket 51 for each of the endless chains 52, and connected to the endless chains 52 is a plurality of interfitting buckets 53. The bucket construction 53 is shown in detail in Figures 5 and 5, and each of the buckets 53 has the same construction. Thus, each bucket 53 includes a wall portion 54 and an arcuate wall portion 55. The side portions of each of the buckets 53 are indicated by the numeral 56 and these side portions 56 converge toward each other for a purpose to be later described. Cutting teeth 57 extend from each of the wall portions 55 for facilitating the excavation of the dirt. The upper sprockets 58 for the chains 52 are mounted on the shaft 47, Figure 5.

The excavator mechanism 50 further includes a means for insuring that the chains 52 remain under proper tension, and this means comprises a post 59 which is slidably mounted in a sleeve 60 that is connected to arms 68 by a pin 61, Figure 1. A washer 62 is circumposed on the post 59 and a stop pin 63 limits upward movement of the washer 62. A second washer 65 is arranged in spaced parallel relation with respect to the washer 62, Figure 1, and a coil spring 64 is interposed between the pair of washers 62 and 65. A sleeve 66 is slidably mounted on the lower end of the post 59, and the sleeve 66 has journaled therein a shaft 67 on which the lower sprockets 51 are mounted. Thus, the spring 64 serves to normally urge the shaft 67 away from the shaft 47 so that the buckets 53 will be maintained in their proper spaced apart relation under tension at all times.

The pair of arms 68 are pivotally mounted on a pin 69 which is journaled in a pair of lugs 70 that extend rearwardly from the brace 40, Figures 1 and 2. Secured to each of the arms 68 is a plate 71, the plate 71 being arranged in diverging relation and the plate 71 serves to prevent any of the dirt that has been excavated from accidentally falling back into the hole H.

A means is provided for guiding the excavated dirt to one side of the machine and trench, and this means comprises a hollow housing 72 which is arranged contiguous to the upper end of the excavating mechanism 50. The hollow housing 72 has pivotally connected thereto by means of securing elements 74, a chute 73. Thus, when the buckets empty the dirt therefrom, the dirt

will be first emptied into the housing 72 and from the housing 72 the dirt will pass down through the chute 73 to one side of the ditch being dug.

A means is provided for regulating the depth of cut of the excavating mechanism and this means comprises a standard 75 which is adjustably mounted in a casing 76, the standard 75 being maintained immobile by tightening a bolt and nut assembly 77. The standard 75 is mounted rearwardly of the machine, and a finger 78 having a curved portion is secured to the lower end of the standard 75, the finger 78 acting as a feeler whereby the depth of excavating or digging will be accurately controlled.

A means is provided for propelling or moving the machine in a horizontal direction, and this manually operable means includes a ratchet 79 which is secured to the rear axle 22. A manually operable lever 83 carries a spring pressed pawl 84 and the pawl 84 is adapted to engage the teeth of the ratchet wheel 79 to cause forward movement of the machine. Thus, the lever 83 is reciprocated or rotated by the driver conveniently sitting on the seat 86 whereby the pawl 84 will rotate the ratchet wheel 79 and this in turn will cause rotation of the shaft 22 so that the wheels 23 will be rotated whereby the machine will be propelled forwardly. The motor 44 as previously described, serves to cause continuous travel of the buckets 53 so that the trench or ditch can be dug as the machine moves along. The spring pressed pawl 84 is slidably mounted in a casing 85 that is secured to the lower end of the lever 83, the lever 83 being pivotally mounted on the shaft 22. A means is provided for preventing accidental rotation of the ratchet wheel 79 in the wrong direction, and this means includes a dog 81 which is slidably mounted in a casing which is secured to the frame 20. A key 82 is provided whereby the dog 81 can be disengaged from the ratchet wheel 79, and a similar key is provided for permitting disengagement of the pawl 84 from the ratchet wheel 79.

A means is provided for raising and lowering the excavating mechanism 50, and this means comprises a rod 87 which has a tube 88 slidably mounted thereon. A clamp 89 is connected to the tube 88, and the clamp 89 is also pivotally connected to a pair of levers 90, Figure 1. The front ends of the levers 90 are pivotally connected to the bracket 41 by pins 91, while the rear ends of the levers 90 are pivotally connected by means of pins 92 to plates 93 which form part of the upper end of the excavating mechanism 50. A suitable handle 94 is connected to the clamp 89 so that by rotating the handle 94 the clamp 89 can be loosened or tightened on the tube 88. The levers 90 can be pivoted about the pin 91 whereby the excavating mechanism 50 can be raised and lowered so that the depth of cutting or digging can be accurately controlled since hydraulic fluid under pressure can be supplied to the tube 88 to cause the tube 88 to move up and down on the rod 87. The excavating mechanism is held in its adjusted position and is prevented from collapsing by conventional control valves that are arranged in the hydraulic fluid circuit that supplies hydraulic fluid to the tube 88. The lower end of the member 87 is pivotally connected to ears 96 which extend upwardly from the frame 20 by means of a pin 95, Figure 4.

A means is provided for pivoting the base 42 so that the tension on the belts 46 can be decreased when desired. This means includes a handle or lever 97 which has its lower end pivotally connected to the frame 20 by a pin arrangement 102, Figure 1. A link 98 is secured to the lower end of the handle 97, and a pin 99 pivotally connects a link 100 to the link 98. A pin 101 serves to pivotally connect the link 100 to the bottom of the base 42. Thus, by shifting the handle 97 about the pivot pin 102, the motor 44 and the base 42 can be pivoted about the pin 43 so that the tension on the belts 46 can be reduced when desired. Thus, should the digging mech-

anism become overloaded or hung on a small object, the tension on the belts may be released by depressing the lever 97 which is attached to the pivoting motor base 42. By quickly releasing the lever 97, the engine momentum applies a definite impact to the belts which is in turn transferred to the digging chain so that it is possible to use a much smaller motor than ordinarily required.

In use, the gasoline engine 44 can be actuated to thereby cause the endless chains 52 to travel since the belts 46 are trained over the drive shaft pulley 48 and the pulley 49. As the chains 52 travel in an endless path, the buckets 53 constantly travel with the chains so that the buckets are filled with dirt. These filled buckets are then moved upwardly from their lowermost position and the dirt empties into the housing 72 and from the housing 72 the dirt is guided to one side of the ditch being dug by means of the chute 73. The excavating mechanism 50 including the buckets 53 can be raised and lowered by manipulating the handle 94 to operate the jack 89. The plate 71 serves to prevent the excavated dirt from accidentally falling back into the trench H. The steering wheel 27 can be used for guiding the machine and the lever 83 can be moved back and forth to propel the machine in a horizontal direction. Thus, by reciprocating the lever 83, the pawl 84 will engage the teeth of the ratchet wheel 79 to rotate the shaft 22 to cause the machine to move forwardly.

From the foregoing, it is apparent that a machine has been provided which will effectively and efficiently dig trenches, ditches and the like. The machine is completely portable and light in weight and can be used by anyone with a minimum amount of skill. With this machine digging time will be greatly reduced and the machine is very complete and compact so that it can be used close to fences and foundations. Also, it is highly maneuverable and will dig tight soil or heavy mud. The all steel buckets 53 are self cleaning and the spoils can be deposited on either side of the trench by means of the chute 73. The finger 78 follows the digger to provide a sharp clean cut ditch. The machine is especially suitable for digging small trenches which are to be used for receiving pipes, conduits or foundation excavations for small dwellings. The gasoline engine 44 may be air cooled and may be provided with a suitable gear reduction unit. The buckets 53 are so constructed that the bottom apron 55 of one bucket forms a back for the following bucket. This construction is advantageous since it serves to clean the spoils from each bucket as they round the upper sprocket. The digging chain is operated in such a way as to enable the spoils to be thrown from the buckets 53 by centrifugal force and these spoils are deposited in the chute 73 after they leave the housing 72. To facilitate the digging, small teeth 57 are secured to each bucket 53. The tension on the belts 46 can be released in the event the digging mechanism becomes overloaded or hung on an object. Thus, to release the tension the lever 97 can be swung in a clockwise direction, Figure 1. Then, by quickly releasing the lever 97, the engine momentum applies a definite impact to the belts and this in turn is transferred to the digging chain so that it is possible to use a much smaller motor than ordinarily would be required. The pawl 84 may be disengaged when the machine is being moved from one location to another. The machine of the present invention is very light in weight.

I claim:

1. In a ditch digging machine, a mobile frame including a pair of spaced apart beams, a bracket extending upwardly from said frame and secured thereto, an excavator mechanism arranged rearwardly of the frame and including a driven shaft adapted to be connected to a power source, a lower shaft arranged in spaced parallel relation below said driven shaft, a pair of sprockets mounted on each of said shafts, endless chains trained over said sprockets,

a plurality of interfitting buckets connected to said chains, each of said buckets including a straight wall portion and an arcuate wall portion, and a pair of side portions, said side portions converging towards each other, a plurality of cutting teeth extending from each arcuate wall portion, a pair of arms pivotally connected to the rear of said frame, a sleeve connected to said arms, a post slidably mounted in said sleeve, a pair of spaced parallel washers mounted on said post, a coil spring 10 circumposed on said post and interposed between said pair of washers, a sleeve slidably engaging the lower end of said post and connected to the lower shaft of said excavating mechanism, a plate secured to each of said arms, said plates being arranged in divergent relation with respect to each other, a hollow housing arranged contiguous to the upper end of said excavating mechanism, a chute pivotally connected to said housing, a casing positioned at the rear ends of said arms, a standard adjustably mounted in said casing, a bolt and nut assembly for maintaining said standard immobile in said casing, a finger having a curved portion secured to the lower end of said standard, and means on said frame for raising and lowering the excavating mechanism.

2. In a ditch digging machine, a mobile frame including a pair of beams, a bracket extending upwardly from said frame and secured thereto, an excavator mechanism arranged rearwardly of the frame and including a driven shaft adapted to be connected to a power source, a lower shaft arranged below said driven shaft, a pair of sprockets mounted on each of said shafts, endless chains trained over said sprockets, a plurality of interfitting buckets connected to said chains, each of said buckets including a

straight wall portion and an arcuate wall portion, and a pair of side portions, said side portions converging towards each other, a plurality of cutting teeth extending from each arcuate wall portion, a pair of arms pivotally connected to said frame, a sleeve connected to said arms, a post slidably mounted in said sleeve, a pair of washers mounted on said post, a coil spring circumposed on said post and interposed between said pair of washers, a sleeve slidably engaging the lower end of said post and connected to the lower shaft of said excavating mechanism, a plate secured to each of said arms, a housing arranged contiguous to the upper end of said excavating mechanism, a chute pivotally connected to said housing, a casing positioned at the rear ends of said arms, a standard adjustably mounted in said casing, a securing assembly for maintaining said standard immobile in said casing, a finger having a portion secured to the lower end of said standard, and means on said frame for raising and lowering the excavating mechanism.
